COMPUTER AUTOMATIC RESET

Leroy A. Nettleton, Brookline, and Henry S. Sommers, Jr., Belmont, Mass., assignors, by mesne assignments, to the United States of America as represented by the Secretary of the Navy

Application January 7, 1946, Serial No. 639,675

6 Claims. (Cl. 318—24)

1

This invention relates to synchros, and more particularly to synchros used to position auxiliary apparatus.

Synchros are well known in the art, and are usually encountered in data transmission systems. When a driven element in data transmission apparatus must be reset at the conclusion of some operation to one certain position and held stationary at that point, mechanical power from some source other than synchros is usually necessary. Generally this source of power is a motor with associated gears or other driving mechanisms which necessarily complicate many systems using synchros.

Therefore the general object of the present invention is to provide for the utilization of a synchro, normally used for data transmission, as a motor to operate a driven element.

It is a further object of the present invention to provide means for switching a synchro so that it may function to transmit data, to operate as a motor, or to lock a driven element.

These and other objects will be apparent from the following specification when taken with the accompanying drawings in which:

Fig. 1 is a schematic diagram of an embodiment of the present invention;

Fig. 2 is a view of one possible cam arrangement;

Fig. 3 is a view of another possible cam arrangement;

Fig. 4 is a schematic diagram of a synchro illustrating a connection for locking it in a stationary position; and

Fig. 5 is a schematic diagram of a synchro illustrating how it may be connected as a motor.

Referring now to the drawings and specifically to Fig. 1, a synchro system is shown wherein unit 10 represents a synchro motor. However, other types of synchro units may be used. Magnetic switch 11 operates upon the energization of magnet 24 when switch 23 is closed to connect the synchro to a data transmission circuit, and when switch 23 is opened the synchro connects to magnetic switch 12. Magnetic switch 12 is operated by magnet 25 and switch 22, the latter being controlled by cam 13. Switches 11 and 12, although shown for convenience as magnetic switches, may be any other suitable switching apparatus. Transformer 14 when connected to a suitable alternating voltage supply, furnishes a voltage pattern at its secondary suitable for locking a synchro unit in a stationary position in a manner known to the art. Capacitor 15 is connected to a stator winding of the synchro motor through

2

switch 16 which is operated by cam 17. The capacitor 15 causes the synchro motor to operate as a two phase induction motor, the running direction being determined by the position of switch 16. Cams 13 and 17 are mechanically connected to the rotor of the synchro motor as indicated by dotted lines 18, 19, 20 and rotation reduction mechanism 21. Magnetic switches 11 and 12 are powered by a suitable supply connected at terminals 28 and 29. A single phase alternating voltage supply, connected at terminals 26 and 27, and 26' and 27', furnishes power to synchro motor 10 and transformer 14.

Fig. 2 illustrates a form of driven element 15 mechanically connecting a cam system, the latter comprising cams 13 and 17, to synchro motor 10. Thus, synchro motor 10 has its rotor shaft 30 operating a small gear 31 which turns large gear 32. Large gear 32 turns shaft 33 on which cams 13 and 17 are mounted. These cams operate switches 22 and 16 respectively. Arrow 34 indicates a point on the periphery of large gear 32 which corresponds in position to the protrusion in cam 13. Arrow 35 is a point adjacent to large gear 32 so determined that if arrows 34 and 35 coincide, cam 13 operates switch 22. It may be further seen that switch 16 is operated one way or the other by cam 17 depending on whether arrow 34 is in one or the other half region of large gear 32 as viewed in Fig. 2.

Fig. 3 illustrates an alternative driven element and cam system mechanically connecting synchro motor 10 and switches 16 and 22. In this figure a single cam 40 replaces cam system 13, 17 (Fig. 2). Cam 40, however, operates switches 16 and 22 in the same relation to large gear 32 as was shown to occur in Fig. 2.

Fig. 4 is a simplified schematic diagram showing how a pattern of voltage is applied to the windings of synchro motor 10 to cause it to lock in a particular stationary position. Transformer 14 is shown with conventional primary and tapped secondary windings. However the synchro may be directly connected to the line voltage supply, or an auto transformer may be used to provide a different excitation level. The process here shown is generally known in the art as locking at electrical zero or "zeroing." This operation is effected when the switching elements of Fig. 1 are operated as will be described below.

Fig. 5 shows in simplified form how the synchro 10 is made to operate as a two phase induction motor. Two stator coils are connected in series across the single phase alternating voltage supply 26 and 27, and the third stator coil is con-

nected to one side of the supply through series capacitor 15. This capacitor provides a shift in phase angle of the current through the third stator coil, so that the resulting effect is two phase stator excitation. This phase shift may be accomplished by any other impedance element, as for example, a resistor or inductor, as is well understood. This two phase excitation produces a rotating magnetic field within the synchro, causing the rotor to revolve in the manner well known for induction motors. Changing the position of switch 16 reverses the direction of rotation because the time relations in the magnetic field are reversed. Induced currents in the laminated core of the synchro's rotor act in the same manner as currents in the rotor of an ordinary motor. Hence the synchro's rotor may be short circuited, open circuited, or closed through a resistance.

Referring again to Fig. 1, it will be shown how the present invention may be used for data transmission, or as an apparatus for resetting and locking a driven element at a predetermined point. When synchro motor 10 is used for data transmission, it is connected by the switching system shown to a data transmission circuit by means of magnetic switch 11 when the movable arms thereof are thrown upward as viewed in Fig. 1. Magnetic switch 11 thus electrically disconnects all other parts of the circuit from the synchro motor.

When synchro motor 10 is used to reset and lock a driven element (such as shown in Fig. 2 or 3) at a predetermined point, magnetic switch 11 is operated to disconnect the synchro motor from the data transmission circuits, and to connect the synchro motor to magnetic switch 12. This occurs when the movable switch arm of switch 11 is thrown downward as viewed in Fig. 1. If switch 22 is not closed, switch 12 is in the downward position. Cam 17 and associated switch 16 then connects capacitor 15 and the single phase alternating voltage supply at 26, 27 to synchro motor 10 through the contacts of switch 12, causing the synchro motor to act as a two phase induction motor. The direction of rotation of the synchro motor is determined by the position of switch 16, which in turn is determined by which side of cam 17 operates switch 16. Being connected as a two phase motor, synchro motor 10 operates the driven element and the cam system in one direction or the other until the protrusion on cam 13 operates switch 22. Switch 22 then operates magnetic switch 12 and throws the movable arms thereof upward as viewed in Fig. 1. This disconnects the synchro motor from capacitor 15 and the single phase supply, terminals 26 and 27, and connects the synchro motor to transformer 14 which furnishes a voltage pattern which locks the synchro motor in a single stationary position, as previously described in connection with the simplified "zeroing" circuit, Fig. 4.

Since changes may be made in the system described, and different embodiments of the present invention may be made without departing from the scope thereof, it is intended that all matter contained in the above description or shown in the accompanying drawings shall be interpreted in an illustrative and not limiting sense, and therefore that the invention is to be limited only by the prior art and the spirit of the appended claims.

What is claimed is:

1. A synchro system comprising a synchro mo-

tor, a driven element mechanically connected to said synchro motor, a cam system mechanically connected to said driven element, a switching system mechanically operated by said cam system, 5 a capacitor and source of voltage, said cam system operating said switching system and causing said synchro motor to be a reversible motor in all but one position of said cam system, and causing said synchro motor to be stationary at the remaining position of said cam system.

2. A synchro system comprising, a voltage source, a capacitor, a synchro, a driven element, rotation reduction means connecting said synchro to said driven element, a cam system connected to said driven element, and switching apparatus operated by said cam system, whereby said capacitor is switched into the circuit between said voltage source and a stator winding of said synchro, said synchro thereby being operative as a reversible two phase motor in all but one position of said cam system, and whereby said capacitor is switched out and voltages from said source selected to lock said synchro are applied to its stator windings at a predetermined remaining position of said cam system.

3. A synchro-automatic reset system comprising a receiver synchro, a voltage source, an impedance element, means connecting said impedance element with said synchro to said voltage source to operate said synchro as a reversible motor, a transformer energized from said source to provide a locking voltage pattern, and switching means operated by said synchro at a predetermined position to disconnect said synchro from said voltage source and said impedance element and connect said synchro to said transformer locking voltage pattern whereby said synchro is locked in said predetermined position.

4. A synchro automatic reset circuit for a synchronous data transmission system comprising a receiver synchro, a voltage source, a locking voltage pattern derived from said source, a phase shifting impedance, switching means disconnecting said synchro from said data transmission system and connecting said impedance with said synchro to said voltage source for operation of said synchro as a reversible motor, and means operated by said synchro at its zero position to disconnect said synchro from said impedance and voltage source and connect said synchro to said locking voltage pattern whereby said synchro is locked at said zero position.

5. In a synchronous data transmission system, an automatically reset circuit comprising, a receiver synchro, an auxiliary voltage supply, a transformer energized from said supply to provide a locking voltage pattern, means to operate said synchro as a reversible motor from said voltage supply, and switching means operated by said synchro at a predetermined position to disconnect said synchro from said voltage supply and to apply said locking voltage pattern to said synchro to lock said synchro in said position.

6. In a remote position indicating system in which the position of a synchronous transmitter is followed by the position of a synchronous receiver, an automatic zero reset circuit comprising, an auxiliary voltage source, a transformer energized from said source to provide a locking voltage pattern, a normally de-energized magnetic switch connecting said receiver to said transmitter, means energizing said switch to disconnect said receiver from said transmitter and to apply voltages from said source to operate

said receiver as a reversible motor, and switching means operated by said receiver at its zero position to disconnect said receiver from said voltage source and to connect said receiver to said locking voltage pattern whereby said receiver is locked at said zero position.
